Primary Examiner — Kelley A Donnelly(74) *Attorney, Agent, or Firm* — Warner Norcross + Judd LLP(57) **CLAIM**

The ornamental design for an overbed table as shown and described.

DESCRIPTION

FIG. 1 is a front perspective view of the overbed table embodying the new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

FIGS. 1-8 show portions of an overbed table in broken lines. The broken line portions do not form part of the claimed design.
